United States Patent Office

Des. 188,122
Patented June 7, 1960

188,122

STILT TOY

Jacob J. Wolski, 210 Midway Drive, New Castle, Ind.

Filed Oct. 30, 1959, Ser. No. 58,130

Term of patent 14 years

(Cl. D34—5)

Fig. 1 is a top plan view of a stilt toy, showing my new design.

Fig. 2 is a bottom plan view thereof.

Fig. 3 is a side elevation view thereof.

Fig. 4 is a rear elevational view thereof.

I claim:

The ornamental design for a stilt toy, as shown.
